UNITED STATES PATENT OFFICE.

JAMES P. HILLARD, OF FALL RIVER, MASSACHUSETTS.

STOP-MOTION IN SPINNING MACHINERY.

Specification of Letters Patent No. 33,037, dated August 13, 1861.

To all whom it may concern:

Be it known that I, JAMES P. HILLARD, of Fall River, in the county of Bristol and State of Massachusetts, have invented a new and useful Mode for Stop-Motions for Railway Drawing-Heads; and I do hereby declare that the following is a full, clear, and exact description of the construction and operation of the same, reference being had to the annexed drawings, making a part of this specification, in which—

Figure 1 is a perspective view; Fig. 2 is a transverse section.

My invention consists in a mode for stopping the operation of a railway drawing machine, when the sliver breaks, or in any way disappears, by the dropping of a lever, or its equivalent, and thereby acting on other devices which change the driving belt from the tight to the loose pulley.

Fig. 1 A' is a double ratchet wheel, hung on a pin at x' ; B' is a latch lever; C' is a lever which raises the latch lever, by means of pin T' across which B' rests. Pin T' being on the opposite side of C' it could not be shown, but is represented by a projection on the top of C'. D' is a latch spring, attached to the slide G' at z' ; E' is a spiral spring attached also to the slide G' at W' ; F' is a wire attached to the lever C'—the right hand end of the spiral spring is permanently secured to the frame of the machine at y .

Fig. 2, A² B² is a lever hung in a movable joint in the stand D²; C² is a cylinder, permanently secured to an arm on lever A² B² and at right angles to it; E' is a slide balance weight, which may be adjusted to any desirable position on B² end of lever A² B²—to partially counterbalance the weight of the cylinder C²; F' is a wire which connects A² B² with C², (see Fig. 1); G² is the belt guide; H² is the belt; I² is the loose pulley; J² J² the sliver; f² f² f² are the receiving rolls; g² g² are the draft rolls; h² h² are the calender rolls.

Operation: The above parts of the stop motion for a railway drawing head, being constructed as herein specified and described; and being attached to a railway

drawing head as herein set forth—the operation may be noted; when the belt H² is forced on the tight pulley by sliding the slide G² to the left hand, the cylinder C² being first placed on the sliver J², the catch on the latch spring catches into the ratchet wheel A' on the underside, and a catch on the latch lever B' also catches into the ratchet wheel A' on the upper side; B' being secured to the frame in a point at p, prevents the ratchet wheel from being turned by the elasticity of the spiral spring. When the sliver breaks, or in any way disappears, A² end of lever A² B², and C², which rest on the sliver,—being adjusted by the slide weight E², so that A² is a trifle heaviest, will drop; and B² end of lever, being attached to lever C' (see Fig. 1) by means of wire F', raises the latch lever B', by means of pin T', and liberates the ratchet wheel; and the spiral spring forces back the slide G'—the belt running through a mortise, or its equivalent, in the end of the slide changes it from the tight to the loose pulley.

I am aware that there are several English inventions which seem to be coincident with mine, but on examination it will be found they severally use cones, trumpets, funnels or mouth-pieces—the several terms mean the same—I hereby disclaim all right to the said inventions viz: to Atkins No. 8363—80 Newton's Journal Vol. 18 p. 145—*ibid.* conjoined series Vol. 30 p. 409—to Daniels English provisional No. 1621 for 1857—Shaw and Robertson's No. 1749 for 1857 and Tempest's No. 25 for 1859. But 85

What I claim as my invention and desire to secure by Letters Patent in the stop motion for railway drawing head, is—

The combination of the cylinder C² constructed and arranged so as to lie on the sliver as shown with the lever A² B² and its adjusting weight E² substantially as above described.

JAMES P. HILLARD.
